CLAIM

The ornamental design for a microwave oven as shown and described.

DESCRIPTION

FIG. 1 is a front perspective view of the microwave oven showing my new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a partial enlarged view of the area '8' as identified in FIG. 1;

FIG. 9 is a front perspective view in a condition that only the button at the side has been depressed;

FIG. 10 is a front view of FIG. 9;

FIG. 11 is a back view of FIG. 9;

FIG. 12 is a left side view of FIG. 9;

FIG. 13 is a right side view of FIG. 9;

FIG. 14 is a top plan view of FIG. 9;

FIG. 15 is a bottom plan view of FIG. 9;

FIG. 16 is a partial enlarged view of the area '16' as identified in FIG. 9;

FIG. 17 is a front perspective view in a condition that both buttons at the side and the lower front right have been depressed;

FIG. 18 is a front view of FIG. 17;

FIG. 19 is a back view of FIG. 17;

FIG. 20 is a left side view of FIG. 17;

FIG. 21 is a right side view of FIG. 17;

FIG. 22 is a top plan view of FIG. 17;

FIG. 23 is a bottom plan view of FIG. 17;

FIG. 24 is a partial enlarged view of the area '24' as identified in FIG. 17; and,

(Continued)

FIG. 25 is another perspective view of the microwave oven showing a use state in which the door has been opened and all buttons have been depressed.

The dot-dot broken lines depict portions of the microwave oven that form no part of the claimed design. The dash-dot broken lines adjacent solid line subject matter in the drawings depict the bounds of the claim and form no part thereof. The dash-dot broken line circles in FIGS. 1, 8, 9, 16, 17 and 24 depict enlarged view indicia and form no part of the claimed design.

1 Claim, 25 Drawing Sheets
